UNITED STATES PATENT OFFICE.

MARTIN CASTRICUM, OF SPRINGFIELD, MASSACHUSETTS, ASSIGNOR TO THE FISK RUBBER COMPANY, OF CHICOOPEE FALLS, MASSACHUSETTS, A CORPORATION OF MASSACHUSETTS.

CORD-SPACING DEVICE.

Application filed June 16, 1924. Serial No. 720,194.

To all whom it may concern:

Be it known that I, MARTIN CASTRICUM, a citizen of the United States of America, residing at Springfield, in the county of 5 Hampden and State of Massachusetts, have invented certain new and useful Improvements in a Cord-Spacing Device, of which the following is a specification.

In the handling of parallel unconnected 10 cords it has been customary to provide as a spacing device a comb constructed in the manner of a lazy-tongs, so that the spacing of the cords may be varied as desired by changing the degree of extension of the 15 tongs structure. For certain uses of such devices, particularly in the handling of cords for the production of the combination of rubber and unwoven cords known as weftless cord fabric, the existing adjustable 20 spacing devices are not sufficiently accurate. In this so-called weftless fabric the cords are usually somewhat separated, and they therefore do not derive lateral support from each other as they do for example in ordinary 25 warp-handling machinery. For this reason, and because of the accuracy required in the production of weftless fabric, improvements in the heretofore proposed devices have become desirable, which it is the purpose of 30 this invention to supply.

Referring to the drawings,

Fig. 1 is a plan of an adjustable comb constructed according to my invention;

Fig. 2 is a fragmentary plan thereof, 35 turned at right angles to Fig. 1 and illustrating the passage of cords therethrough;

Fig. 3 is a side elevation corresponding to Fig. 2;

Fig. 4 is a plan view of a collar appearing 40 in Fig. 3; and

Fig. 5 is a side view thereof.

The comb is carried on a framework composed of crossed links 10 pivoted together at points 11 and also at their central points 45 of intersection so as to form a lazy-tongs structure. Suitable nuts secured concentric with certain of the central pivots, but not shown on the drawings, engage separate threaded portions on a shaft 12 extending 50 the entire width of the comb. This shaft is secured in a base plate 13 which also serves to guide the tongs structure in its expanding and contracting movement. The pitch of the threaded portions of the shaft 55 vary with their distance from the center so

that the various portions of the tongs are given the proper proportional movements. Details of the device so far described need not be given since such devices are well known in the art.

Mounted on each of the links 10 of one of the two parallel series which go to make up the tongs structure (Fig. 1) are comb-carrying bars 14, each carrying a series of 60 equally spaced pins 15 between which the cords 16 pass. The spacing of the pins on the successive bars is such that the first pin on a bar is on the same line, drawn parallel to the travel of the cords, upon which would be the pin beyond the last, were such a pin 65 placed on the bar just previous in order. This is shown in Fig. 2 where the pin 15^a, the initial one on bar 14^a, is spaced, at right angles to the line of travel of the cords, one cord space from pin 15^b, the last one on 70 bar 14^b.

It will be apparent from Fig. 2 that in 75 passing between the pins the cords 16 are deflected in their path, and are caused to bear constantly on one side of a pin. This 80 insures a constant and accurate positioning of the cords. In the deflection of the cords they pass by one side of a pin and by the other side of the next succeeding pin, receiving in this passage a momentary reverse 85 curvature. That cord 16^a which would normally pass by on the right of pin 15^b, however, meets with no succeeding pin to impart to it this reverse curvature, and a misalignment 90 would result were no measures taken 95 to correct it. The means which I have adopted to correct this error will now be described.

Pin 15^a, which is the first of the series on bar 14^a, is provided with a collar 17, preferably provided with a cord receiving groove 18, and shown in detail in Figs. 4 and 5. This collar is secured to the pin, as by being made a press fit thereon, at a considerable 100 elevation above the general path of travel of the cords 16 (Fig. 3). Pin 15^b, the last of the series on bar 14^b, is made shorter than the others, so that cord 16^a, which is elevated by the collar 17, will pass over its top. It will be observed that the cords after 105 having made their reverse curve around the pins are, in the position of adjustment shown, in substantial alignment with the center of the pin with which they first contacted. By the described special arrange- 110

ment of the pins guiding the cord 16^a the latter will pass pin 15^b in substantial alignment with its center, and will therefore lie in proper spaced relation to the other cords.

5 The pins 15^a and 15^b act with relation to those cords adjacent to cord 16^a in a manner similar to the other pins.

The described construction is repeated on each of the bars 14, and gives an expanding 10 comb in which the cords are equally and uniformly spaced irrespective of the condition of adjustment of the comb. Bunching and irregular spacing of cords in the rubberized sheet may by this means be completely eliminated.

Having thus described my invention, I claim:

1. A comb structure for guiding a series of parallel cords comprising a series of pins 20 supporting bars arranged parallel to each other but at an angle to the path of travel of the cords, and a series of pins upon each bar, the pins of the several bars being

spaced substantially evenly along lines parallel to the path of travel of the cords; 25 the initial pin on each bar being provided with means for raising a cord above the rest, and the final pin on each bar being made short to permit a cord so raised to travel over it.

2. An expanding comb structure comprising a lazy-tongs, means for expanding or contracting the lazy-tongs, and pins carried by the members of one parallel series of links forming the lazy-tongs; the pins as 30 an entire series being spaced substantially evenly as referred to lines drawn through their centers parallel to the path of travel of the cords, the initial pin on each link being provided with means for raising a cord 35 above the rest, and the final pin on each link being made short to permit a cord so raised to travel over it; whereby a uniform spacing of cords is obtained in any position of adjustment of the comb.

MARTIN CASTRICUM.
